(57) **CLAIM**

What is claimed is the inlet door assembly of a hopper wagon, as shown and described.

DESCRIPTION

FIG. 1 depicts a perspective top view of a hopper wagon in accordance with the invention with the inlet door assembly in the closed position;

FIG. 2 depicts a perspective top view of the hopper wagon with the inlet door assembly of FIG. 1 in the open position; FIG. 3 depicts an end view of the hopper wagon with the inlet door assembly of FIG. 1 in the closed position;

FIG. 4 depicts an end view of the hopper wagon with the inlet door assembly of FIG. 1 in the open position;

FIG. 5 depicts an upper end view of a portion of the hopper wagon with the inlet door assembly of FIG. 1 in the closed position; and,

FIG. 6 depicts a side view of a portion of the hopper wagon with the inlet door assembly of FIG. 1 in the closed position. The broken lines shown in the drawings are for the purpose of illustrating portions of the article and environmental structures that form no part of the claimed design.
